UNITED STATES PATENT OFFICE.

JACOB CONRAD BITTENBENDER, OF CONSTANTINE, MICHIGAN.

CAR-COUPING.

SPECIFICATION forming part of Letters Patent No. 310,021, dated December 30, 1884.

Application filed August 22, 1884. (No model.)

To all whom it may concern:

Be it known that I, JACOB C. BITTENBENDER, a citizen of the United States of America, residing at Constantine, in the county of St. Joseph and State of Michigan, have invented certain new and useful Improvements in Car-Couplers; and I do hereby declare the following to be a full, clear, and exact description of the invention, such as will enable others skilled in the art to which it appertains to make and use the same, reference being had to the accompanying drawings and to letters or figures of reference marked thereon, which form a part of this specification.

15 My invention relates to car-couplings; and it consists in the improvements described and set forth, whereby a simple, durable, and efficient device is produced.

In the accompanying drawings, forming a part of this specification, Figure 1 is a perspective view of one end of the car, with some of my improved couplings applied thereto. Fig. 2 is a longitudinal section of the same.

A represents the body of the draw-head, which is secured upon the under central portion of the car, as indicated, and has the usual rear extension, B, embraced by a spring, a, to provide a spring-bearing for the draw-head. The said draw-head is provided with a recess, b, at one side of its front portion, in which is pivoted the rear end of the shank portion c of a metallic hook, C. A second recess, d, formed parallel with the first-mentioned recess, extends back in the body of the draw-head. A pin, e, serving as the pivot for the hook C, pierces the said draw-head, so as to pass transversely through both recesses. An angle-lever, D, is pivoted by a pin, f, in the rear portion of the recess d, and is of the form shown in Fig. 2. The portion of the draw-head A forming the bottom of the recess d is inclined downward to the front of the said draw-head as illustrated in Fig. 2, and the lower portion of the lever D is formed to bear upon and accord with said inclined surface. The upper free end of the said lever D is perforated for the attachment of one end of a cord or cable, g, which is attached to a drum, E, keyed upon a vertical shaft, F, designed to be operated by the brakeman or operator. The nose or upper front portion, h, of the hook C is perforated for the attachment of a second cord or cable, i, which is also connected to the drum E.

The operation of the coupling is as follows: 55 The arrangement on the adjacent couplings of recesses, hooks, and levers will be the reverse of each other, as shown in Fig. 2. As the two draw-heads approach each other each hook-rod C will slide up and enter the recess d of the opposite draw-head and engage the pins e, arranged transversely therein, thereby insuring both hooks combining in the coupling operation. Now, when either of the vertical shafts are rotated so as to revolve the drums, 65 the traction exerted on the cords g i will respectively cause the same to lift the hook out of engagement with the pin e of the opposite draw-head, and at the same time tilt the lever D on its pivot f, so as to cause the lower 70 portion of said lever to contact with the head of the hook of the opposite draw-head and lift it out of engagement with the pin e, thereby effecting, upon the single operation of either one of the shafts F, the simultaneous 75 disengagement of both hooks C from the pin e. Loops j are arranged on the front of the draw-heads, and serve as buffers, to limit the approach of said draw-heads to each other and insure the entrance of the hooks C in the 80 recesses d sufficient only to engage the pins e.

I claim—

1. The combination, in a car-coupling, of a draw-head provided with recesses b d, a pin, e, transversely piercing said recesses, a hook 85 pivoted in the recess b, and an angle-lever, D, pivoted in the rear portion of the recess d, and adapted to move independently of said hook, to contact with and lift the same, cords or cables attached to said hook and angle-lever, and operating means, substantially as specified.

2. The combination, in a car-coupling, of a draw-head provided with recesses b d, pins e, transversely piercing said recesses, a hook, 95 C, pivoted in the recess b, and an angle-lever, D, pivoted in the rear portion of the recess d, and having its lower portion inclined to correspond with the inclined bottom of the recess d, cords or cables attached to said hook and to said angle-lever, operating drum E, and buffer j, substantially as set forth.

In testimony whereof I affix my signature in presence of two witnesses.

JACOB CONRAD BITTENBENDER.

Witnesses:
